(57) **CLAIM**

The ornamental design for a level measuring device, as shown and described.

DESCRIPTION

FIG. 1 is a top perspective view showing a level measuring device having a float slidably mounted on a mounting pole; FIG. 2 is a bottom perspective view showing the level measuring device of FIG. 1; FIG. 3 is a front elevational view of the level measuring device of FIG. 1; FIG. 4 is a rear elevational view of the level measuring device of FIG. 1; FIG. 5 is a left-side elevational view of the level measuring device of FIG. 1; FIG. 6 is a right-side elevational view of the level measuring device of FIG. 1; FIG. 7 is a top view of the level measuring device of FIG. 1; FIG. 8 is a bottom view of the level measuring device of FIG. 1; FIG. 9 is a perspective view showing the level measuring device of FIG. 1 with the float at a position different from that in FIG. 1; FIG. 10 is a perspective view of the mounting pole of the level measuring device of FIG. 1; and, FIG. 11 is a cross-sectional view of the mounting pole of FIG. 10. The mounting pole is shown separately in FIGS. 10 and 11 for clarity of illustration.
